UNITED STATES PATENT OFFICE.

SAMUEL BOORN, OF LOWELL, MASSACHUSETTS.

PICKER FOR LOOMS.

Specification of Letters Patent No. 31,776, dated March 26, 1861.

To all whom it may concern:

Be it known that I, SAMUEL BOORN, of Lowell, in the county of Middlesex and State of Massachusetts, have invented a new and useful Improvement in Movable Shuttle-Box Rawhide Pickers for Looms; and I do hereby declare the same to be fully described in the following specification and illustrated in the accompanying drawings, of which—
10 Figure 1, is a side view; Fig. 2, a front edge view, and Fig. 3, a longitudinal section of a picker provided with my invention or improvement.

My improvement has reference to the 15 socket head which contains the horn cushion or bushing against which the point or nose of the shuttle acts while the shuttle is being ejected from one of the shuttle boxes. This socket head and its cushion or bushing are 20 represented in the drawings at A, and B.

The socket a, for reception of the cushion B, is made tapering as shown in Fig. 3.

In constructing the socket head, I form it with two recesses or notches a', a', which 25 I arrange as shown in Figs. 1, and 2, viz., on opposite sides of the larger base of the conical cushion B, and at right angles or thereabout with the part C, of the picker. By so notching the said part A, we not only 30 afford the horn cushion B, a chance to expand laterally, without powdering under the blows of the shuttle, but enable the principal part of the spreading of the cushion to take

place toward and in the notches. The 35 notches, also facilitate the removal of the surplus of the cushion without injury to the socket head, as they enable such surfaces to be removed by means of a saw.

After a horn cushion has been in use some time, it becomes indented by the conical 40 point of the shuttle. If held closely, on all sides of its larger base or that end which encounters the shuttle, such cushion will soon become powder or be reduced somewhat as a piece of stone or other hard substance 45 is reduced by the point of a drill. Owing to the picker, when in use being made to operate with a movable series of shuttle boxes, its cushion will shortly become worn transversely or in a direction at right angles 50 with the part C. The tendency of the picker cushion to spread from its center is more in such direction than any other. The utility of the recesses or notches a', a', in preserving the picker cushion from destruction, and in other respects, has been found 55 in practice to be very great.

I claim therefore—

My improved, movable shuttle box picker, as made with its head A, notched with respect to its shuttle cushion B, substantially 60 in manner and for the purpose as described.

SAMUEL BOORN.
